J. J. McCULLOCH.

END GATE.

APPLICATION FILED MAR. 20, 1920.

1,386,882.

Patented Aug. 9, 1921.

By *Watson E. Coleman*
Attorney

UNITED STATES PATENT OFFICE.

JOHN J. McCULLOCH, OF POMEROY, IOWA.

END-GATE.

1,386,882.

Specification of Letters Patent. Patented Aug. 9, 1921.

Application filed March 20, 1920. Serial No. 367,573.

To all whom it may concern:

Be it known that I, JOHN J. McCULLOCH, a citizen of the United States, residing at Pomeroy, in the county of Calhoun and State of Iowa, have invented certain new and useful Improvements in End-Gates, of which the following is a specification, reference being had to the accompanying drawings.

10 This invention relates to certain improvements in end gates for wagons and it is an object of the invention to provide a novel and improved device of this general character which may be readily applied and 15 which can be effectively locked in closed position the same being an improvement on the form of end gate disclosed in my pending application Serial No. 224,280, filed March 23, 1918.

20 It is also an object of the invention to provide a gate of this general character comprising two relatively movable sections and wherein one of the sections is provided with means operating independently of the remainder of the sections for holding said sections in closed position.

25 The invention consists in the details of construction and in the combination and arrangement of the several parts of my improved gate whereby certain important advantages are attained and the device rendered simpler, less expensive and otherwise more convenient and advantageous for use, as will be hereinafter more fully set forth.

30 The novel features of my invention will hereinafter be definitely claimed.

35 In order that my invention may be the better understood, I will now proceed to describe the same with reference to the accompanying drawings, wherein:

Figure 1 is a view in elevation, with portions broken away, of an end gate constructed in accordance with an embodiment of my invention and in applied position;

40 Fig. 2 is a fragmentary horizontal sectional view taken through the lower portion of the device as illustrated in Fig. 1;

45 Fig. 3 is a view partly in elevation and partly in section illustrating the means carried by a side wall of the wagon box for holding the end gate in applied position;

50 Fig. 4 is a view, enlarged, partly in section and partly in elevation, illustrating one of the swinging latches carried by the lower section of the end gate in locking position;

55 Fig. 5 is a fragmentary view in front ele-

vation of the structure illustrated in Fig. 4; and

Fig. 6 is a fragmentary view partly in section and partly in top plan of the structure shown in Fig. 5.

As disclosed in the accompanying drawings, B denotes the tail portion of a wagon box and the opposed faces of the side walls of said box adjacent the rear end thereof are provided with the vertically disposed cleats 1. Secured to the opposed faces of the cleats 1 and extending entirely therewith are the metallic straps or plates 2 provided with the outwardly directed hook members 3, 3^a, and 3^b, for a purpose which will hereinafter be more particularly referred to.

My improved end gate, as herein disclosed, comprises two sections A and A', 75 having their closed marginal portions hingedly connected, one to the other as indicated at 4, whereby said sections are capable of independent relative movement and especially as relates to the lower section A'. The 80 gate when in applied position, abuts against the strips 5, overlying the opposed faces of the straps or plates 2, and at a predetermined point inwardly of the outer longitudinal margins of said straps or plates 2. 85

Secured to the outer face of the section A of the gate, at the upper corners thereof are the plates 6 which extend beyond the vertical margins of the gates, and the extended portion of each of said plates is provided 90 with a vertically disposed slot 7, through which is adapted to be directed a hook member 3. By this means the upper section A of the gate is effectively supported in applied position and may be readily applied 95 or removed in accordance with the occasions of practice.

Secured to the outer face of the lower section A' of the gate at the upper corners thereof are the plates 6' extending beyond the vertical margins of said section and the extended portions thereof are provided with the vertically disposed slots 7' through which the hook members 3^a are adapted to extend when the section A' is in closed position. 100

The lower marginal portion of the section A' adjacent each vertical margin thereof has extending outwardly therefrom a pair of bearings 8 aligned transversely of the body B when the gate is in applied position 110 and rotatably supported by said bearings is

a rod or shaft 9. The outer end of the shaft is provided with a rock arm 10 terminating in a laterally and outwardly connected extension 11, which is adapted to engage the 5 upstanding point *a* of the hook member 3^b for holding the lower section A' in closed position.

The opposite end portion of the shaft 8 is provided with the arm or lever 12 which 10 affords means for imparting the requisite rotation or rocking movement through the shaft 9. The arm or lever 12 by contact with the section A' of the gate limits the downward movement of the arm or lever 12 15 and also of the rock arm 10. As is particularly illustrated in Fig. 4, it is to be noted that such arm or lever 12 is arcuate and bowed in a direction away from the section A' when the lever or arm 12 is in its lower- 20 most position so that the same may be readily grasped by the operator when it is desired to swing the arm or lever 12 upwardly to effect a release of the gate section A'.

25 My improved end gate as herein disclosed is particularly adapted for use in the hauling of grain or similar material and when the end gate is in applied position it is to be noted that leakage or escape of the load is 30 effectually prevented. By rendering the locking means as afforded by the shafts 9 and their concomitant parts inoperative by throwing the arms or levers 12 upwardly, the lower section A' may be readily swung 35 into an open position independently of the section A as the necessities of practice may require.

From the foregoing description, it is thought to be obvious that an end gate constructed in accordance with my invention 40 is particularly well adapted for use by reason of the convenience and facility with which it may be assembled and operated and it will also be obvious that my invention is 45 susceptible of some change and modification

without departing from the principles and spirit thereof and for this reason I do not wish to be understood as limiting myself to the precise arrangement and formation of the several parts herein shown in carrying out my invention except as hereinafter claimed.

I claim:

The combination with a wagon box, plates carried by the side walls thereof, at the tail 55 of the box, an end gate comprising two pivotally connected sections, one of said sections constituting an upper section and the other of said sections constituting a lower section, plates secured to the upper portion 60 of each section, said plates extending beyond the vertical margins of said sections and having a vertically disposed slot in the protruding portions, said slots being in vertical alignment, hook members extending outwardly from the plates and coacting with the slots, a third hook member on each plate and in vertical alignment with the aforementioned hook member, the lower hook members 65 having a greater distance between the hook portion and the plate than the upper hook members, and holding means carried by the lower portion of the lower section and coacting with the lower hook members, said means comprising rods each of which 70 is provided with rock arms to engage the outer portion of the hook members, the opposite end portion being provided with an operating lever, said lever swinging downwardly to arrange the rock arm in working 75 engagement with the coacting hook member and being limited in its downward movement by the gate.

In testimony whereof I hereunto affix my signature in the presence of two witnesses. 80 85

JOHN J. McCULLOCH.

Witnesses:

J. L. MORRIS,
HENRY JANSSEN.
